EVAPORATOR

Ray A. Sandberg and Oscar F. Gottlieb, North Chicago, Ill., assignors to Oakes Products Corporation, North Chicago, Ill., a corporation of Michigan

Application December 14, 1934, Serial No. 757,441

7 Claims. (Cl. 62—126)

This invention relates to a sheet metal evaporator having an individually formed header.

More specifically this invention relates to an evaporator for refrigerators having sheet metal shells defining a plurality of passageways for refrigerant therebetween and forming the side and bottom walls of a sharp freezing chamber and provided with a separate tubular header secured to the ends of the sheet metal shells.

10 In the co-pending application of Ray A. Sandberg entitled "Evaporator unit and process", Serial No. 736,183 filed July 20, 1934, there is described and claimed a method of making evaporators for refrigerators by placing two metal sheets in juxtaposition with a thin brazing shim or sheet therebetween and heating the so formed pack to brazing temperatures for joining the sheets together along all inner contacting surfaces. The sheets are stamped prior to the brazing operation so as to form embossed portions thereon which provide ducts for the refrigerant. The sheets are also stamped with semi-cylindrical depressions which register with a similarly formed depression in the other sheet to form a 25 tubular header.

We have now found that in some instances it is not desirable to subject the header material to the brazing temperature. We have therefore now provided an evaporator unit in which the 30 header is formed separately from the brazed together sheets which provide the refrigerant passageways. The sheets are bent into the desired form to confine a sharp freezing chamber and the separately formed header is soldered, brazed 35 or welded to the ends of the sheet. The header is in communication with the passageways formed between the sheets. The evaporator of this invention therefore provides for the production of sheet metal evaporator units without subjecting the header portion of said units to the temperatures used in securing the sheets together.

Since the header portion generally has a more extended surface which must resist pressures within the evaporator unit than does the brazed 45 together shell portion we can form the header of thicker gauge metal than the metal in the shell section. In this manner the pressure resisting strengths of the two portions can be balanced without wasting metal as was heretofore 50 necessary when the unit was formed in one piece.

It is, therefore, an object of this invention to provide an evaporator for refrigerators having 55 separately formed headers and sheet metal walls defining a sharp freezing chamber.

A further object of this invention is to provide an evaporator unit having a separately formed header and brazed together shell defining a plurality of passageways therebetween in communication with said header.

5 A main object of this invention is to provide an evaporator for refrigerators having a header portion formed from relatively thick gauge metal and a brazed together sheet metal shell portion formed from thinner gauge metal and secured to the header in air tight relation whereby the strengths of the two portions can be balanced and the evaporator can be prepared from a minimum amount of material without reducing the pressure resisting capacity of the unit.

15 A specific object of this invention is to provide an evaporator unit for refrigerators composed of separately formed sheet metal shells providing passageways for refrigerant and defining the side and bottom walls of a sharp freezing chamber 20 and a header secured to the ends of said shell without being subjected to the temperatures used in forming the shell.

25 Other and further objects of this invention will be apparent from the following detailed description of the annexed sheets of drawings which form a part of this specification.

On the drawings

Figure 1 is a top plan view of an evaporator 30 unit according to this invention.

Figure 2 is a front elevational view of the evaporator unit shown in Figure 1.

Figure 3 is an enlarged cross sectional view taken substantially along the lines III—III of 35 Fig. 2 with part in elevation.

Figure 4 is a broken plan view of the outer sheet metal shell before it is bent to define a sharp freezing chamber and showing in dotted lines the inner shell as it is positioned against 40 the outer shell.

Figure 5 is a cross sectional view taken substantially along the lines V—V of Figure 4.

Figure 6 is a broken plan view of the embossed sheet of metal forming the inner shell of the 45 evaporator unit.

As shown on the drawings

In Figure 1 the reference numeral 10 indicates generally an evaporator unit composed of a tubular metal header 11 and a sheet metal shell portion 12 joined with said header in a manner to be hereinafter described. The shell portion 12 is formed from an outside sheet 9 shown in Figure 4 and an inside sheet 15 shown in Fig- 55

ure 6 which are placed in juxtaposed relation and joined together by the thin brazing shims sandwiched therebetween according to the method described and claimed in the Sandberg co-pending application Serial No. 736,183 above referred to.

The sheet 9 is stamped to form a plurality of parallel semi-cylindrical corrugations 13 extending longitudinally across the sheet. These corrugations 13 provide passageways for the refrigerant as will be hereinafter described. The ends of the sheet 9 are bifurcated as shown at 14 to provide cut away portions between the corrugations 13 for a purpose to be hereinafter described.

The inner sheet 15 is stamped to provide thereon a pair of beads 16 and 17 extending transversely of the sheet intermediate the ends and sides thereof. A plurality of oval shaped embossed portions 18, 19, 20 and 21 are also stamped 0 into the sheet 15 near one side of the sheet.

The ends of the sheet 15 are stamped to provide thereon a plurality of semi-cylindrical corrugations 22. These corrugations 22 extend away from the ends of the sheet only for a short distance as shown in Figure 6. The portions of the sheet between the corrugations 22 are bifurcated as shown at 23.

The sheets 9 and 15 are placed in juxtaposed relation as shown in Figure 4 so that the corrugations 22 of the sheet 15 register with the ends of the corrugations 13 of the sheet 9. The bifurcated ends 14 of the sheet 9 also register with the bifurcated portions 23 of the sheet 6. As is more fully described in the co-pending application of Ray A. Sandberg, Serial No. 736,183, thin metal shims composed of a brazing metal are sandwiched between the sheets 9 and 15.

The sheet 15 is preferably formed somewhat wider than the sheet 9 so that its sides may be bent around the sides of the sheet 9 to provide flanges 24 and 25 for holding the sheet together. The so formed pack, with the metal shims therebetween, is then heated between dies to a temperature sufficient to melt the metal shims so that they can fuse into the adjoining surfaces of the sheets 9 and 15 to secure the same together. The brazed metal 26 so formed (Figure 5) has filleted portions 27 at each corrugation 13 and 22. This fillet 27 is formed, when the brazing metal melts down, by capillary action of the sheet metals 9 and 15. The fillets 27 strengthen the so formed together shell and prevent leakage between the corrugated portions of the shell.

The so brazed together shell is then bent into the shape shown in Figure 2 to provide the bottom 28, sides 29 and 30 and sloping top portions 31 and 32 of a sharp freezing compartment 33.

The beads 16 and 17 on the inner sheet 15 of the shell portion 12 provide supports for an ice tray 35 shown in dotted lines in Figure 2. The bottom 28 may serve as a support for a second ice tray 36.

The oval shaped embossed portions 18 and 21 of the sheet 15 form back stops for the ice tray 35 while the embossed portions 19 and 20 form back stops for the ice tray 36.

The separately formed tubular header 11 is next secured to the shell portion 12 between the sloping top portions 31 and 32. The tubular header can be prepared by a stamping or drawing operation and the open end closed by soldering a cap member thereon to form a closed header compartment, or by folding a sheet stamped with two semi-cylindrical depressions to form a tube and soldering the ends of the sheet together.

The tubular header 11 shown in Figures 1, 2 and 3 is formed by a drawing operation and has a curved end 37 integral with the tubular side walls and a front cover 38 welded to the tubular side walls to close the header compartment. 5

As shown in Figure 3, the header 11 is provided with outwardly extending flanges such as 39 defining circular openings such as 40. The openings 40 are positioned to register with the stamped corrugations 13 and 22 of the sheets 9 10 and 15. These corrugations together form cylindrical tubes which are adapted to snugly fit over the flanges 39 of the header tube 11. The tube 11 is securely soldered, brazed or welded to the sheet portion 12 by means of welds 42 formed 15 around the ends of the corrugations 13 and 22. The bifurcated ends 14 and 23 of the sheets 9 and 15 provide openings 41 between each corrugation. These openings 41 facilitate the soldering or welding operation in that they permit more 20 clearance for the manipulation of a soldering or welding tool, and make it possible to extend the weld 42 entirely around the flange 39.

From the above description it is evident that we have provided an evaporator unit for refrigerators composed of a sheet metal shell portion providing a plurality of passageways for refrigerant and a separately formed header portion secured to the ends of said shell portion. In heretofore known sheet metal evaporator units 30 the header was formed integral with the shell portion and was necessarily of the same gauge metal as the shell portion. By forming our evaporator in two separate portions, it is possible to form the header from heavier gauge metal 35 than is used in forming the shell portion so that it can withstand higher pressures. It is known that the header metal must be stronger than the metal of the shell portion since the refrigerant ducts in the shell portion are reinforced by the 40 larged brazed areas between each small corrugation. Therefore when the header portion is formed integral with the shell portion, it is necessary to use sheet metal of a thickness sufficient to withstand the pressure in the header. This 45 thickness is more than is required for the shell portion and since most of the metal is used for forming the shell portion, a large proportion of the metal is wasted. Since the evaporators of this invention are preferably formed of brass this 50 waste amounts to a considerable item in mass production. Evaporators having separately formed headers and shell portions can readily be made from two different types of metal. For example the shell portion can be formed of brass 55 while the header can be formed of steel.

Furthermore, in processes of welding sheet metal portions together to form the shell portion or expansion chamber of an evaporator unit the sheet metal must necessarily be heated to temperatures sufficient to cause fusion of the metal itself along the welds. This heating of the sheet metal necessarily weakens the tensile strength of the metal and its resistance to distortion. When the header portion of the evaporator unit is formed as a separate element, according to our invention, this header portion is not subjected to these high welding temperatures and all of its metallurgical characteristics are preserved. The metal forming the header portion can be worked cold thereby retaining its strength and allowing the use of lighter metal than could be used if the header portion were an integral part of the unit and subjected to the temperatures used in 65 70 75

- welding the sheet metal portions together to form the expansion chamber.
- We are aware that many changes may be made and numerous details of construction may be varied through a wide range without departing from the principles of this invention, and we, therefore, do not purpose limiting the patent granted hereon otherwise than necessitated by the prior art.
10. We claim as our invention.
1. An evaporator unit for refrigerators comprising an inner shell of sheet metal bent to form the bottom and side walls of a sharp freezing chamber, beads embossed on said shell to provide ice tray supports, additional beads embossed on said shell near the back thereof to provide stops for ice trays, cylindrical embossed corrugations on the ends of said shell extending inwardly from the ends for a short distance, an outside shell circumscribing said inner shell and provided with a plurality of parallel corrugations extending therearound and registering with the corrugations on the ends of the inner shell to form tubular passageways therebetween, a separately formed tubular header extending transversely of the ends of said shells and having a plurality of outwardly extending annular flanges registering with the tubular portions of the shell, and welds joining said tubular portions with said annular flanges to securely mount the header with the shells in communication with the passageways formed by the shells.
  2. An evaporator unit for refrigerators comprising a sheet metal shell portion providing elongated parallel passageways for refrigerant, said shell portion being bent to confine a sharp freezing chamber, a header welded to the ends of said shell, said header having a plurality of outwardly extending annular flanges registering with the passageways formed by the shell portion and secured thereto in air tight relation and openings between each of the passageways to facilitate joining the header to the shells.
  3. In an evaporator for refrigerators, a sheet metal shell portion providing a plurality of passageways for refrigerant, said passageways defining circular openings at the ends of the shell, a tubular header having a plurality of outwardly extending annular flanges on each side thereof defining a plurality of circular openings for registering with the shell openings and means for securing the shell to the flanges of the header to provide an air tight joint therebetween with the openings of the shell in alignment with the openings in the header.
  4. In a sheet metal evaporator, a tubular header having a plurality of annular flanges extending laterally from each side thereof to define a row of spaced circular openings on each side of the header, a brass sheet metal shell portion formed from two embossed brass sheets secured together to define a plurality of expansion ducts for refrigerant, said ducts being tubular at the ends thereof to define circular openings adapted to snugly fit over the annular flanges of the header and means for securing the tubular ends of the shell to the header in air tight relation.
  5. An evaporator unit for refrigerators comprising a brazed together sheet metal portion formed from relatively thin gauge sheet metal, said portion providing a plurality of refrigerant passageways, and a separately formed header portion of thicker gauge metal having openings defined by laterally extending annular flanges which are welded to the ends of said sheet metal portion in communication with the passageways therein whereby the pressure resisting capacities of said portions are equalized and the unit is formed from a minimum of material.
  6. In a sheet metal evaporator, a tubular header formed from heavy gauge sheet brass and having a plurality of annular flanges extending laterally from each side thereof to define a row of spaced circular openings on each side of the header, a brass sheet metal shell portion formed from two embossed brass sheets of thinner gauge than the header metal secured together to define a plurality of expansion ducts for refrigerant, said ducts being tubular at the ends thereof to define circular openings adapted to snugly fit over the annular flanges of the header and a weld extending completely around said tubular ends to secure the shell to the header in air tight relation.
  7. An evaporator unit comprising a pair of embossed secured together metal sheets defining a plurality of parallel passageways for refrigerant, said sheets being bent to define a sharp freezing chamber and having inwardly extending top portions in space opposed relation, a tubular header in the space between said top portions having openings along the sides thereof defined by laterally extending annular flanges for seating in the passageways defined by the secured together sheets and recessed cuts in the ends of said sheets between each of the passageways defined thereby, said sheets being secured to said header around each of the annular flanges thereof.
